UNITED STATES PATENT OFFICE

170,616

COMBINED ADJUSTABLE LAMP STAND AND TABLE

Milton R. Yarger, Morgantown, W. Va.

Application April 27, 1951, Serial No. 14,995

Term of patent 14 years

(Cl. D33—14)

To all whom it may concern:

Be it known that I, Milton R. Yarger, a citizen of the United States, residing at Morgantown, in the county of Monongalia and State of West Virginia, have invented a new, original, and ornamental Design for a Combined Adjustable Lamp Stand and Table, of which the following is a specification, reference being had to the accompanying drawing, forming a part thereof.

Fig. 1 is a perspective view of a combined adjustable lamp stand and table, showing my new design.

Fig. 2 is a similar view thereof in open adjusted position.

I claim:

The ornamental design for a combined adjustable lamp stand and table, as shown.

MILTON R. YARGER.
